UNITED STATES PATENT OFFICE.

ABRAHAM B. LANDIS, OF WAYNESBORO, PENNSYLVANIA.

CHANGE-SPEED GEARING.

1,017,893.

Specification of Letters Patent.

Patented Feb. 20, 1912.

Application filed August 27, 1909, Serial No. 514,953. Renewed December 9, 1911. Serial No. 664,762.

To all whom it may concern:

Be it known that I, ABRAHAM B. LANDIS, a citizen of the United States, residing at Waynesboro, in the county of Franklin and 5 State of Pennsylvania, have invented certain new and useful Improvements in Change-Speed Gearing, of which the following is a specification.

My said invention consists in an improved construction of variable speed frictional driving gearing, embodying a multiplicity of frictional surfaces for engagement between the driving and the driven part, of a form and arrangement capable 10 of being indefinitely multiplied to secure the power and speed required, whereby the power may be transmitted with a comparatively light pressure between the bearing faces and the wear and strain upon said 15 parts thus reduced to a minimum, and a gearing of the character mentioned provided which will be very durable in use and comparatively inexpensive to maintain; also one wherein the change in speed can be adjusted gradually and continuously without 20 any jar or undue strain upon the different parts and in which the pressure of the frictional contact between the parts will be automatically regulated by the load, or power 25 required to carry the load, all as will be hereinafter more fully described and claimed.

Referring to the accompanying drawings which are made a part hereof and on which 30 similar reference characters indicate similar parts, Figure 1 is a top or plan view of a gear casing inclosing a frictional gearing of my improved construction, Fig. 2 an end elevation thereof, Fig. 3 a central longitudinal section through the same on the dotted line 3—3 in Fig. 1, Fig. 4 a similar view showing the parts in a different position, Fig. 5 a cross section on the dotted line 5—5 in Fig. 3, and Fig. 6 a cross section 40 on the dotted line 6—6 in Fig. 3.

In said drawings the portions marked A represent the casing or frame, B the outside cylinder inclosing the gearing, and C the inside cylinder.

50 In many of the details of construction and arrangement the gearing shown is substantially the same as that forming the subject matter of my application No. 399,447, filed October 28, 1907, the present invention 55 consisting largely in a modification of the construction there shown.

The frame or casing A is any suitable supporting part for the purpose and adapted to be secured to the machine with which the gearing is to be used. At each end it is provided with end pieces or standards A' and A², respectively, in which are mounted long sleeves of parts 10 and 11, which serve as bearings for long hubs 12 and 13 extending from the outer face of disks 14 and 15, which are mounted on the shafts 16 and 17, respectively. Said parts 10 and 11 are of the form of eccentric disks with long sleeves, the faces of the disks being adjacent and the sleeves being secured in the standards A' and A² by clamping bolts b and dowel pins b'. The shaft 16 is journaled at one end in a bearing formed in the interior of the hub 12 near the disk 14 and at its other end is journaled in a bearing 18 formed in the part 11 a distance to one side of the bearing therein for sleeve 13 and is adapted to have a longitudinal movement in its bearings. The shaft 17 is journaled at one end in a bearing in the sleeve 13 near the disk 15 and at its opposite end in a bearing formed in the part 10 a distance to one side of the bearing therein for the sleeve 12. Said shafts 16 and 17 are thus mounted in their bearings parallel with each other and are arranged one to be the driving and the other the driven shaft. In Fig. 1 I have shown a driving pulley P on the outer end of a shaft 45 coupled to shaft 16 and said shaft will be considered the 90 driving shaft and 17 the driven shaft in the description of the construction, although it will be understood, of course, that the operation may be reversed and the power applied to shaft 17 and taken from the shaft 95 16. The sleeves of the parts 10 and 11 thus serve as the bearings for the hubs 12 and 13, which serve as the supports for the shafts 16 and 17, which are connected to rotate therewith and permitted to slide therein by 100 the engagement v', as shown in Fig. 5, the several parts being arranged as best shown in Fig. 3. The disk 14 with the elongated hub 12, which extends out through the bearing in the part 10, is formed with a shoulder 105 near its inner end and a coiled spring 19 is mounted around the shaft between said shoulder and a collar 20 rigidly secured to the outer end of said shaft beyond the end of said hub. Adjacent to disk 14 a series 110 of disks 21 are arranged on shaft 16 and with said disk 14 are adapted to slide there-

on, being secured from rotation by engagement between longitudinal grooves v in the shaft (see Fig. 6) and inwardly projecting correspondingly formed lugs v' around the 5 aperture in the disks, as best shown in Fig. 5. Adjacent to the inner disk 21 a disk 22 is rigidly mounted on said shaft 16 preferably by a screw-threaded connection. A series of disks 23 are similarly mounted on 10 shaft 17 adjacent to the disk 15 with a disk 24 rigidly secured on the shaft adjacent to the inner disk of the series. Shaft 17 is mounted to slide in its bearings and provided with a spring similar to the spring 15 19 on shaft 16. The faces of the disks 21 and 23 are formed tapered, the thickness of said disks decreasing from the point of connection with the shaft toward their peripheries.

20 Eccentric rings 26 and 27 are mounted respectively on the eccentric disks on the inner ends of the parts 10 and 11, said rings being formed with shoulders on their inner faces on which are mounted steel rings 28 25 and 29 each formed with a groove in its outer face serving as one-half of a ball-race.

The cylinder C is formed with recesses at 30 its ends within which are mounted steel rings 30 and 31 formed with grooves on their faces. Said cylinder is mounted with said rings supported on balls 32 and 33, mounted in the ball-races between the rings 28 and 30 at one end and 29 and 31 at the opposite end, in the recesses formed in the 35 adjacent faces of said rings 26 and 27. On the outer end of ring 26 is formed an annular flange in the outer surface of which are formed worm-gear teeth with which a worm-gear 35 on a transverse shaft 36, journaled in bearings 37 and 38 on the top of the casing, is adapted to engage. A hand-wheel 39 is provided on one end of shaft 36 by which it may be turned.

The eccentric rings 26 and 27 are rigidly 45 connected to rotate together on the eccentric disks of parts 10 and 11 by the cylinder B which is mounted on said rings and secured thereto by means of screws 37 inserted through perforations in said cylinder into 50 said rings at intervals throughout the circumference thereof. The turning of the shaft 36 will, therefore, operate, through the connection between worm 35 and the teeth on the flange of ring 26, to turn the casing 55 composed of the rings 26 and 27 and the cylinder B on the eccentric disks of parts 10 and 11 and also carry with it the inner cylinder C which is supported concentrically therewith upon the ball-bearings 32 and 60 33 in the ball-races on the inner adjacent shoulders of said rings 26 and 27 respectively.

In the interior of ring C are formed longitudinal V-shaped grooves, as most plainly indicated in Fig. 5, and a series of annular disks

40 are mounted therein at one end to engage between the disks 21 on the shaft 16 and another series of annular disks 41 are mounted at the other end to engage between the faces of disks 23, the disk 40 at the outer end of the series engaging between the face of disk 14 and the end disk of series 21, while the disk 40 at the opposite end of the series engages between the fixed disk 22 and the disk 21 at that end. At the other end the outer disk 41 engages between the disk 15 on the shaft 17 and the adjacent disk 23, while the disk 41 at the other end engages between the fixed disk 24 and the adjacent disk 23. Said disks 40 and 41 are formed with V-shaped projections at intervals around their peripheries adapted to engage with the V-shaped grooves in the internal face of the cylinder C, so that they are held to revolve with said cylinder while being permitted to slide longitudinally thereof.

The driving pulley P is mounted upon a shaft 45 formed at its inner end with a thimble 46 which fits over the projecting end of shaft 16 around collar 20 on its outer end. Said thimble is formed with slots in its sides formed with tapered or cam edges. Radial studs 47 with anti-friction rollers 48 thereon project from the opposite sides of collar 20 and engage in the slots in the sides of thimble 46 bearing upon the cam-shaped edges, which are arranged at an angle so that as the power is applied to pulley P the edges will operate against the rollers 48 to pull outwardly upon the shaft 16, which through the fixed disk 22 serves to crowd the surfaces of the disks 21 and 40 together so that the motion of shaft 16 will be transmitted through said disks 21 and the disks 40 and from said disks 40 to the cylinder C, which rotating upon the ball-bearings 32 and 33 carries with it the disks 41. The shaft 17 being coupled to the work, in the same manner as shown and described for the coupling of the shaft 16 to the power, it will be seen that the resistance of the work will also tend to draw disk 24 against the inner disk 41 of that series, and bring said disks 41 into frictional engagement with the faces of disks 23 and thus transmit the power to said shaft 17, which is geared to the work. As before stated, and as will be readily understood, the operation may be reversed, if desired, and will be identical regardless of which shaft is used as the driving shaft.

It will be noted that the inner edges of the annular disks 40 and 41 have narrow thickened rims 50 which constitute the bearing faces between the respective sets of disks so that the engagement will be between this narrow portion only and a portion of the disks 21 and 23 of corresponding width, insuring that the operation of the parts will be without any binding action.

The operation is as follows: Referring to Fig. 3, it will be noted that the disks 21 are in engagement with the thickened inner rims of the disks 40 at a point close to the shaft 16, while disks 41 engage with the disks 23 near their peripheries. These engagements are always maintained by the action of springs 19, insuring a starting contact at all times. The driving shaft 5 being started the motion is thus transmitted from shaft 16 to the cylinder C at the slowest speed and greatest power while cylinder C, through the engagement between the disks 41 and 23, serves to transmit the power 10 to shaft 17 with the greatest possible leverage so that shaft 17 will be driven at a reduced speed from that of the shaft 16, but with great power. In Fig. 4 the cylinder B, with the rings 26 and 27 has been turned by 15 the worm-gear 35 on shaft 36 upon the eccentric bearings on disks of parts 10 and 11 to throw the engagement of the sets of disks to the other extreme points, the disks 21 engaging the rims of disks 40 at their outer 20 edges, while the disks 41 engage the sides of the disks 23 close to the shaft 17. Thus it will be seen, shaft 16 being the driving shaft, that shaft 17 will be driven at a speed much greater than the speed of said shaft 16. 25 Any intermediate position in the engagement between the two sets of disks can be effected by the adjustment of cylinder B through the medium of the crank-wheel 39 on shaft 36 and the engagement of the 30 worm-gear 35 with the worm-teeth on the flange of ring 26, all as will be readily understood.

By this means the speed can be adjusted 35 gradually and constantly without any sudden change and the strain of the load, or the power, will operate to automatically adjust the pressure of the frictional contact between the several sets of disks, the greater the load the more pressure and as the load 40 lightens the pressure will decrease, so that the strain and wear upon the parts will be no more than required to carry the work placed upon the gearing. The wearing parts being also inclosed in the tight casing 45 B are protected from dirt and foreign substance and any interference with their operation therefrom.

Having thus fully described my said invention, what I claim as new, and desire to 50 secure by Letters Patent, is:

1. In a change speed gearing, the combination of the casing, a driving and a driven shaft journaled in said casing parallel to each other, a plurality of disks on each of 55 said shafts mounted to move longitudinally, a revoluble part surrounding both of said shafts, a plurality of disks carried by said revoluble part a part of which are arranged to engage with the disks on one shaft and a 60 part of which are arranged to engage with

the disks on the other shaft, and means for adjusting the point of engagement, substantially as set forth.

2. In a change speed gearing, the combination of the casing, a driving shaft journaled therein, a driven shaft journaled therein in parallel with said driving shaft, a series of disks mounted on the driving shaft to rotate therewith and slide therein, a series of disks mounted on the driven shaft to rotate therewith and slide thereon, a fixed disk at the inner end of each series of disks on each shaft, means for sliding each of said shafts longitudinally in its bearings, a revoluble part surrounding both of said shafts, a series of disks mounted in said revoluble part to rotate therewith and slide longitudinally, a part of said disks being arranged to engage with the disks on the driving shaft and a part being arranged to engage with the 70 disks on the driven shaft, substantially as set forth. 75

3. A change speed gearing comprising a casing, a driving shaft, a driven shaft, a series of friction disks on each of said shafts, a 80 revoluble part surrounding both of said shafts, a series of disks carried by said revoluble part, a part of which are arranged to engage with the disks on the driving shaft and a part of which are arranged to engage with the disks on the driven shaft, substantially as set forth. 90

4. A change speed gearing comprising a casing, a driving shaft mounted to slide longitudinally in bearings therein, a series 100 of disks slidably mounted thereon to rotate therewith, a driven shaft journaled in said casing parallel with said driving shaft, a series of disks slidably mounted thereon to rotate therewith, an eccentrically mounted 105 revoluble part surrounding both of said shafts and the disks thereon, a series of disks carried by said revoluble part, a part of which are arranged to engage with the disks on the driving shaft and a part of which are arranged to engage with the disks on the driven shaft, and means for turning said eccentrically mounted revoluble part for adjusting the point of frictional contact between said several series of disks, substantially as set forth. 110 115

5. A change speed gearing comprising a casing, two parallel shafts journaled in said casing, a series of disks on each of said shafts, an eccentrically mounted revoluble part surrounding said shafts and disks, and a series of disks carried by said eccentrically mounted revoluble part arranged to engage with each of the series of disks on said respective shafts, substantially as set forth. 120 125

6. A change speed gearing comprising a casing, two shafts mounted therein parallel with each other, a series of friction disks mounted upon each, an eccentrically mounted cylindrical casing surrounding said shafts, 130

- a cylinder mounted to rotate within said casing concentric therewith, disks carried by said cylinder arranged to engage with the friction disks on said respective shafts, and 5 means for adjusting said casing carrying said cylinder, substantially as set forth.
7. A change speed gearing comprising a casing, parallel shafts journaled in said casing, a series of friction disks mounted on 10 each shaft, a rotary cylinder surrounding said shafts and mounted on eccentric bearings, said eccentric bearings, a series of disks carried by said cylinder a part of which are arranged to engage with the friction disks 15 on one shaft and a part of which are arranged to engage with the series of disks on the other shaft, substantially as set forth.
8. A change speed gearing comprising a casing, parallel shafts mounted to slide longitudinally in bearings in said casing, a series of sliding disks mounted on each of 20 said shafts to rotate therewith, a fixed disk at the inner end of each series, means for sliding said shafts longitudinally, a rotary cylinder eccentrically mounted surrounding said shafts and disks, a series of disks carried by said rotary cylinder and mounted to slide longitudinally therein, a part of 25 which are adapted to engage between the series of disks on one shaft and a part of which are adapted to engage between the series of disks on the other shaft, and means for adjusting said eccentrically mounted cylinder, substantially as set forth.
- 30 9. A change speed gearing comprising a casing, parallel shafts journaled therein and mounted to slide longitudinally in their bearings, a rotary part surrounding said shafts, a series of friction disks mounted on 35 each of said shafts, and a series of disks mounted on said rotary part arranged to engage with the respective series of disks on said shafts, substantially as set forth.
10. A change speed gearing comprising a 40 casing, parallel shafts mounted therein, a series of longitudinally movable friction disks mounted on each of said shafts, a rotary part surrounding said shafts, a series of longitudinally movable disks carried by 45 said rotary part, a part of which are adapted to engage with the disks of one shaft and a part of which are adapted to engage with 50

the disks of another shaft, and means for sliding said shafts longitudinally for securing the frictional driving contact, substantially as set forth. 55

11. A change speed gearing comprising a casing, parallel shafts mounted in bearings in said casing, a series of slideable disks mounted on each shaft, a revoluble part surrounding said shafts, a series of slideable disks carried by said revoluble part, part of said disks being arranged to engage between the disks in one shaft and part between the disks on another, and means for sliding said 60 several disks to create a frictional driving contact between them, substantially as set forth. 65

12. A change speed gearing comprising a casing, parallel shafts mounted in bearings in said casing, a series of slideable disks mounted on each shaft, a revoluble part surrounding said shafts, a series of slideable disks carried by said revoluble part, parts of 70 said disks being arranged to engage between the disks on one shaft and part between the disks on another, and means for creating frictional driving contact between said disks by the power transmitted, substantially as 75 set forth. 80

13. A change speed gearing comprising two parallel shafts each having a series of disks slidably mounted thereon, ring disks surrounding said shafts and engaging said disks and means for holding said disks in 85 frictional driving contact by the power transmitted, substantially as set forth.

14. A change speed gearing comprising two parallel shafts each having a series of disks slidably mounted thereon, ring disks 90 surrounding said shafts and engaging said disks, means for normally holding said disks in contact, and means for giving pressure to said disk for frictional driving contact by the power transmitted, substantially as set 95 forth.

In witness whereof, I, have hereunto set my hand and seal at Waynesboro, Pennsylvania this 25th day of August, A. D. nineteen hundred and nine.
